UNITED STATES PATENT OFFICE.

GEORGE W. MOORES, OF NEW ORLEANS, LOUISIANA.

GIRTH-BUCKLE.

SPECIFICATION forming part of Letters Patent No. 357,684, dated February 15, 1887.

Application filed June 4, 1885. Serial No. 167,673. (No model.)

To all whom it may concern:

Be it known that I, GEORGE W. MOORES, of New Orleans, parish of Orleans, and State of Louisiana, have invented new and useful 5 Improvements in Girth-Rings; and I do hereby declare that the following is a full and exact description of the same, reference being had to the accompanying drawings, and to the letters of reference marked thereon.

10 This invention is a girth-ring of improved construction, based upon the ring covered by my Letters Patent No. 310,144, dated December 30, 1884, as will be hereinafter described.

In the drawings, Figure 1 represents a front 15 view of my improved girth-ring; Fig. 2, a sectional view; Fig. 3, a sectional view with the girth in place; Fig. 4, an end view, and Figs. 5 and 6 views illustrating the manner of using the improved ring.

20 To enable others skilled in the art to make my improved ring, I will proceed to describe fully the construction of the same.

A represents the ring or frame or D-shaped frame, consisting of a curved upper portion 25 having parallel side bars, a^a , united below by transverse bars a^a in the manner described in the patent before referred to. The upper portion, a^2 , however, it will be observed, is bent outward from the normal plane of the 30 ring or frame in such manner that the point X, which supports the free end of the buckle-tongue, is removed some distance from the normal plane, as shown in Figs. 3 and 4. The lower transverse bar, a^3 , is also modified in construction by bending out the center of the 35 same at the point X', Figs. 1 and 3, by which means the proper space is afforded for the hinged end of the tongue.

B represents a buckle-tongue hinged to the lower transverse bar of the ring or frame, as 40 shown. By means of this construction the ring or frame is adapted to hold the girth in the manner described in the previous patent, and also to buckle to the proper strap depending from the saddle. 45

By means of the bend in the upper portion, a^2 , the point of the tongue is held away from the normal plane of the ring or frame, and the tongue itself is prevented from resting on the transverse bar. 50

By means of the bent portion in the lower transverse bar, a^3 , the proper space is afforded for the hinged end of the tongue. 55

The base portion may be a ring or frame, or a square metal piece, or a piece of any other proper form. It is possible by the employment of this device to unite many parts of the harness without sewing.

Having thus fully described my invention, what I claim as new, and desire to secure by 60 Letters Patent, is—

The improved girth ring or frame, having the parallel bars a^a , forming the lower portion of the frame, united below by the transverse bars a^a , and having the vertical bend 65 in the portion a^2 , the lateral bend in the lower transverse bar, a^3 , and the buckle-tongue B, as described.

This specification signed and witnessed this 22d day of May, A. D. 1885.

GEO. W. MOORES.
